United States Patent Office.

CHARLES L. THIERY, OF BOSTON, MASSACHUSETTS.

Letters Patent No. 96,632, dated November 9, 1869.

IMPROVEMENT IN MANUFACTURE OF WATCH-CASES.

The Schedule referred to in these Letters Patent and making part of the same.

Be it known that I, CHARLES L. THIERY, of Boston, in the county of Suffolk, and State of Massachusetts, have made an invention of a new and useful Manufacture of Watch-Cases; and I do hereby declare that the following, taken in connection with the drawings which accompany and form part of this specification, is a description of my invention, sufficient to enable those skilled in the art to practise it.

Figures 1 and 2 are cross-sections of a watch-case, in the production of which my invention is embodied.

Heretofore, watch-cases have been made up of several pieces of metal, and brazed or soldered together.

The "centre," so called, is made of a strip of metal, bent into a circle, and its ends abutted together and brazed, the glass-bezel, so called, being produced in the same way.

In watches of English manufacture, the back and centre are immovable; that is to say, the back is not, as in Swiss and American watches, hinged to the centre, so as to be opened, but is formed in an independent piece, and brazed to such centres.

My invention is applicable to cases of any manufacture, but is especially valuable in the manufacture of English watch-cases.

The invention consists in forming the different portions of a watch-case in homogeneous pieces of metal, without joints or solder. For instance, in producing a case for watches of English make, the back and centre are struck up or produced in one entire homogeneous piece of metal, the "glass-bezel" being formed in the same way, and applied in the usual manner.

For American, Swiss, or other watches, with the back and dial-cover hinged to the centre, the latter is to be "struck up," or otherwise produced, from a ho-

mogeneous piece of metal, the "glass-bezel," as before mentioned, being produced in the same way, and applied in the manner now common to watches.

In the accompanying drawings, I have adopted an English watch-case with which to illustrate my invention, the centre of such case being shown at *a* and its back at *b*, such parts, as before mentioned, being produced, by proper machinery, from one piece of metal, and without joints or solder.

Fig. 2, of the drawings, is a section taken through the longest area of the "centre" of the case, this "centre," in itself, being the same, whether applied to an English or other-manufactured case. As will be perceived, this centre is in one solid piece of metal, without joint or seam.

The advantages of my invention are comprised in a few words, the watch-case produced by means of it being cheaper and better than any heretofore made. Cheaper, because it is produced, by suitable machinery, from a plain sheet of metal, in a fraction of the time now required to produce it; and better, in that it has no seams, which require very nice fitting, or solder, to braze those seams.

Claim.

What I claim, and desire to secure by Letters Patent, is—

The manufacture of watch-cases, in the manner shown and described.

CHARLES L. THIERY.
